SHOE AND METHOD OF MAKING SAME

Vilem Forschner, New York, N. Y.

Application April 18, 1941, Serial No. 389,153

3 Claims. (Cl. 12—142)

My invention relates to footwear and more particularly to shoes and methods of making same.

One object of my invention is to provide a method by means of which the placing of an upper onto a last prior to its attachment to the sole is eliminated.

A further object of my invention is to provide a method by means of which a shoe with a sole having an upwardly extending flange may be manufactured, wherein the edge of the upper attached to the outside of the flange is folded and contacts the flange with the exterior face of the material of the upper.

Another object of my invention is to provide a method by means of which shoes having a shirred upper may be manufactured without deformation of the wrinkles of the upper during the attachment of the upper to the sole.

Still another object of my invention is to provide a method by means of which a shoe with a sole having an upwardly extending flange may be manufactured wherein the upper with its lining is attached to the outside of the flange and the inside of the flange is covered by a strip of lining attached to the upper on top of its lining.

In order to carry out my invention into practice I use a method of making shoes comprising the steps of preparing an upper having material in excess of the material required for a proper fitting on the wearer's foot, providing means on said upper for taking in the material thereof so as to shape same for a proper fitting on the wearer's foot, and attaching the upper to a sole.

The above mentioned objects and advantages as well as other objects and advantages will be more fully disclosed in the following specification reference being had to the accompanying drawings forming part of this specification, wherein:

Fig. 1 is a perspective view of a shoe manufactured according to my method.

Fig. 2 is a longitudinal cross-section of the shoe taken on line 2—2 of Fig. 1.

Fig. 3 is a transverse cross-section of the shoe taken on line 3—3 of Fig. 1.

Fig. 4 is a perspective view of a molded sole with an upwardly extending flange illustrating the first step of the attachment of the upper to the sole (only a portion of the upper being shown in said figure).

Fig. 5 is a sectional view of the upper and the sole taken on line 5—5 of Fig. 4.

Figs. 6—8 illustrate various subsequent steps of the attachment of the upper to the sole.

Fig. 9 is a perspective view of the shoe illustrating the upper in position after having been turned over.

Fig. 10 is a cross-sectional view of the shoe similar to that shown in Fig. 3, illustrating the steps of contacting the upper.

Fig. 11 is a plan view of the exterior face of the spread out upper,

Fig. 12 is a plan view of the interior face of the spread out upper,

Figs. 13—20 illustrate various embodiments of the connection between an upper and a sole according to my method,

Fig. 21 is a fragmentary cross-section of a different embodiment of a shoe illustrating the connection between the quarter and the sole,

Fig. 22 is a fragmentary perspective view of a shoe manufactured according to a different embodiment of my method,

Fig. 23 is a cross-section of the shoe shown in Fig. 22, taken on line 23—23 of Fig. 22, and

Fig. 24 is a fragmentary longitudinal section of the sole and upper similar to that shown in Fig. 5, illustrating the manufacture of the shoe according to a different embodiment of my method.

Referring now to Figs. 1 and 2, 30 generally indicates the sole, 32 generally indicates the heel secured to the sole in any suitable manner, and 34 generally indicates the upper attached to the sole according to my method. In the embodiment shown in said Figs. 1 and 2, the upper 34 comprises a vamp 36, a quarter strip 38 and a back-strap or heel-strap 40, both secured to the vamp in suitable manner.

The vamp 36 forming the main portion of the upper in the style of shoe shown in the drawings is cut from or stamped out of a flexible material, such as leather, fabric, straw or the like, and this material may be plain or plaited. As may be seen from the shape of the spread out vamp 36 illustrated in Fig. 11, the vamp has material in excess of the material required for a proper fitting on the wearer's foot.

In preparing the upper, a lining 42 (Figs. 11 and 12) of a shape corresponding to that of the vamp 36 is attached to the latter by a seam 44. Then, three casings 46, 48, 50 are formed by sewing together the vamp and the lining along the seams 52, whereupon a hole 54 is cut into the wall of each casing on the exterior face of the vamp. Now, two strings generally indicated by 56 and 58 are placed into each of the casings.

Each string consists of an elastic 60 or 62 respectively and a pulling string 64 or 66 respectively attached to one end of the elastic. The strings 56 and 58 are placed into the casings in such a way that the pulling strips 64 and 66 project from the holes 54 and the ends of the elastics 60 and 62 project from the casings at the edge of the vamp. Now, a curved strip 68 of lining is placed on top of the lining 42 and is secured to the latter by a seam 70. Said seam also secures the elastics 60, 62 to the casings 46, 48, 50 and attaches the lining 42 to the vamp 36 near the edge thereof. Then the projecting ends of the elastics 60 and 62 may be severed by scissors or the like. Although according to Figs. 11 and 12 the holes 54 are on the exterior face of the vamp, they could

be cut into the wall of the casing on the lining face, if desired.

In accordance with the design of the shoe shown in the drawings, both ends of a shirred back-strap 40 having an elastic 72 therein and one end of a quarter strip 38 are sewed on the vamp.

The steps of the attachment of the upper prepared in the manner described above to a molded sole 30 having an upwardly extending flange 74 are illustrated by Figs. 4-9.

According to Fig. 4, at first the edge 76 of the vamp and the edge 78 of the quarter strip (see Fig. 11) are attached to the outside of the flange 74 by a seam 80 with the interior face of the upper outward, i. e. the exterior face of the vamp 36 contacts the flange and the lining 42 of the vamp is on the outside. Then the unshaped upper is turned over in the direction of the arrow A shown in Fig. 5, so that the upper is brought into the position shown in Figs. 6 and 9 with its exterior face outward. As best shown in Fig. 6, the turning over of the upper after its attachment to the sole causes a folding of the edge of the upper attached to the sole. Preferably, after the turning over of the upper, the still free end 84 of the back-strap 38 is also sewed on the vamp 36. Now, the strip 68 is gripped by hand or by a suitable implement and pulled in the direction of the arrow B as shown in Fig. 7, until the edge 82 of the strip 68 tightly contacts the edge 84 of the flange 74, so that said edge 84 of the flange causes a discernible ridge on the outside of the upper at 86 (see Fig. 8). Thereupon, the strip 68 is pasted on or cemented to the inside of the flange 74 and the sole 30 as shown in Fig. 8. Furthermore, the upwardly extending portion of the quarter strip 38 is turned around the edge of the flange 74 so that it is brought into the position shown in Fig. 2, whereupon said portion of the quarter strip 38 is pasted on or cemented to the inside of the flange 74 and the sole 30.

As pointed out above, the upper has material in excess of the material required for a proper fitting on the wearer's foot, and as best shown in Fig. 9, i. e. in the style of a shoe shown in the drawings the vamp 36 thereof would not properly fit on the wearer's foot 88 indicated by dash lines in said figure. Therefore, the upper must be shaped for a proper fitting on the wearer's foot after its attachment to the sole and its having been turned over by taking in the excess material. For this purpose the following steps are carried out: The pulling strings 64 and 66 of each casing are gripped and pulled until the ends of the elastics 60 and 62 of a predetermined length for a certain size of the shoe project from the hole 54. Thereby the material of the vamp 36 and its lining 42 is shirred, as best shown in Fig. 10. Now, the projecting ends of the elastics 60 and 62 are connected with each other by a seam 90 and the pulling strips 64 and 66 are severed. The ends of the elastics connected with each other are pushed back into the hole as shown in Fig. 3, and the hole and said ends become practically invisible by the shirring effect of the vamp, as best shown in Fig. 1.

Fig. 2 indicates the proper fitting of the upper on the wearer's foot 88 after the shirring of the upper.

For the above described shaping of the upper no last is inserted into the shoe, as the proper selection of the length of the elastics for a certain size of the shoe assures a proper fitting of the upper on the wearer's foot.

At a suitable point during the manufacture of the shoe the heel 32 (Fig. 2) is secured to the sole 30, a shank 92 is attached to the upper surface of the sole 30 and a sock-lining 94 is cemented to the sole on top of the shank 92 and the margins of the quarter strip 38 and the strip 68 of a lining. As may be seen from Fig. 2 the entire inside of the shoe including the inner face of the flange 74 is covered by a lining constituted by elements 38 and 68 so that the shoe is comfortable to wear.

My method of making shoes is not limited to the type of shoe shown in Figs. 1-12. A great number of modifications are possible.

According to Fig. 13, for example, the vamp comprises only the material 36 and the lining 42, and a strip of lining to be cemented to the inside of the flange 74 is omitted. Of course, in a shoe manufactured without said strip of lining, the inner face of the flange 74 is not covered and the edge of the flange is not rendered discernible on the outside of the upper.

Furthermore, according to Fig. 14, the lining of the vamp 36 may also be omitted.

It may be mentioned that in all the embodiments shown in Figs. 1-14 the seam 80 is invisible on the outside of the shoe, as the upper has been turned over after its attachment to the sole with its interior face outward.

Furthermore, my method of making shoes by preparing an upper having material in excess of the material required for a proper fitting on the wearer's foot, attaching the upper to a sole and shaping the upper after its attachment to the sole by taking in the material of the upper for a proper fitting on the wearer's foot may also be carried out without the turning over process of the upper. Figs. 15-17, for example, illustrate the attachment of the upper with its exterior face outward to the outside of the flange 74 of a sole 30. Fig. 15 illustrates the use of a lining 42 and the strip of lining 68, Fig. 16 illustrates the use of the lining 42 only, and according to Fig. 17 the vamp 36 has no lining at all.

Moreover, according to my invention an upper having material in excess of the material required for a proper fitting on the wearer's foot may be attached to any type of sole, and any type of connection between the sole and the upper may be used.

Fig. 18, for example, illustrates a sole 31 having an angle-shaped welt 96 attached thereto, and the upper is attached to the outside of the upwardly extending flange of the welt 96.

According to Fig. 19, for example, the upwardly extending flange of the sole 33 is formed by cutting a channel 98 into the edge of the sole and bending upward the portion 100 of the sole. The upper having excess material is attached to the portion 100 and shaped after its attachment thereto in the manner described above.

According to Fig. 20 the upper is attached to a flat sole 35, and, of course, is shaped by taking in the excess material thereof.

Moreover, instead of attaching the upper to the outside of the flange of a sole, the upper may be attached to the inside of the flange, if desired.

My methods also permit the attachment of the upper to an insole instead of an outside.

Furthermore, the upper may be attached to the sole by cementing instead of sewing, if desired.

Moreover, the upper may be of various forms. For example, instead of using a quarter strip 38 and a backstrap 40 as shown in Figs. 1 and 2, a full quarter 108 may be used as shown in Fig. 21.

In the above described embodiment the excess material of the upper is taken in by shirring same by means of elastics having pulling strips attached thereto. If desired, said pulling strips could be omitted and elastics of greater length than necessary could be used; after the pulling out of a portion of the elastics and connecting the elastics with each other to fix the length of the elastics remaining in the casings for a proper fitting of the upper on the wearer's foot, the superfluous ends of the elastics would be severed in the same manner as the pulling strips are severed in the embodiment described above.

Furthermore, instead of using two strings 56 and 58 in each of the casings, a single string of sufficient length projecting from the hole 54 in the form of a loop could be used. Moreover, conventional tapes of fabric could be used for the strings instead of elastics.

The number and the arrangement of the casings for the strings to contract the material of the upper in wrinkles may be chosen in accordance with the design of the shoe.

Instead of taking in the excess material of the upper by means of strings any other convenient means for taking in the material of the upper may be used. According to Figs. 22 and 23, for example, the material of the upper is taken in by means of a body 104 inserted into the upper. The material of the upper is gathered by means of a strip 106 holding the body 104 in its position. The strip 106 is tightened by a bow which, in turn, is fastened by a stitch. Instead of using a disc-like body 104 as shown in the drawings a body of a different shape may be used. If this type of taking in the material is used, further means are necessary to tie the shoe for properly holding same on the wearer's foot. For example, a casing with an elastic could be arranged on the upper like the casing 46 in the embodiment shown in Figs. 1 and 2. Fig. 22, however, shows a different embodiment according to which only the side portions 108, 110 of the upper are shirred by strips 112, 114 arranged in casings and secured to the walls of the casings during the manufacture of the shoe. The middle portion 116 of the upper remains unshirred during the manufacture of the shoe and may be shirred by the wearer of the shoe by means of a shoelace 118 or the like.

Instead of taking in the excess material of the upper by contracting means as described above, the upper could be shaped to the form of the wearer's foot by cutting out the excess material and joining the edges formed by the cuts.

According to the methods described above the upper having excess material is shaped after its attachment to the sole. Under certain conditions, however, the upper may be shaped prior to its attachment to the sole or during its attachment to the sole. In such a case a single elastic of a predetermined length is placed into each of the casings 46-58. The holes 54 are omitted. Now, both ends of each elastic may be secured to the wall of the casing, so that the upper is shirred in accordance with the form of the wearer's foot. Then the upper is attached to the outside of the flange 74 of the sole 30 with its interior face outward as shown in Fig. 24. Thereupon the upper may be turned over while the elastics are stretched. After the turning over of the upper the latter has already its proper shape. Moreover, instead of attaching both ends of a single elastic to the wall of the casing when the upper is prepared, only one end of the elastic of a pre-

determined length may be secured in each casing to the wall thereof, and the other end of the elastic may be secured to the casing simultaneously with the attaching of the upper with its interior face outward to the outside of the flange 74, so that the upper is shaped during its attachment to the sole. In this case the upper is also turned over while the elastics are stretched.

I have described preferred embodiments of my invention, but it is clear that numerous changes and omissions may be made without departing from the spirit of my invention.

What I claim is:

1. A method of making shoes comprising the steps of preparing an upper having material in excess of the material required for a proper fitting on the wearer's foot, securing the edge of a strip of lining to the interior face of the upper by a seam near the edge of the upper to be attached to the flange of a sole having an upwardly extending flange, attaching the unshaped upper with the interior face outward to the outside of said flange of the sole, turning over the unshaped upper so as to bring its exterior face outward, pulling said strip of lining tightly around said flange for placing said seam above said flange and adjacent thereto, attaching the free portion of said strip of lining under tension to the inside of the flange and the sole for a tight contact between the edge of the flange and the strip of lining near said seam so as to render discernible the edge of the flange on the exterior face of the upper, and shaping the upper after its having been turned over for a proper fitting on the wearer's foot.

2. In a turnover shoe the combination of a relatively rigid sole having an upwardly extending flange, an upper attached to the outside of the flange, the edge of said upper being folded and contacting the flange with the exterior face of the material of the upper, said upper having material in excess of the material required for a proper fitting on the wearer's foot, means on said upper for contracting the material thereof in wrinkles, said upper being shaped by said means for a proper fitting on the wearer's foot, and a strip of lining secured to the interior face of the upper above said flange and adjacent thereto by a seam, said strip being fastened under tension to the inside of the flange and the sole for a tight contact between the edge of the flange and the strip of lining near said seam whereby the edge of the flange is rendered discernible.

3. A method of making shoes comprising the steps of preparing an upper having material in excess of the material required for a proper fitting on the wearer's foot, attaching a lining to said upper, forming at least one transverse casing by sewing together the upper and the lining, cutting a hole in the wall of the casing, placing means for contracting the material of the upper into said casing, securing said means to the wall of the casing and having a portion of said means project from said hole, attaching the unshaped upper with the interior face outward to a sole, turning over the unshaped upper so as to bring its exterior face outward, and shirring the upper after its having been turned over by gripping the projecting portion of the contracting means, pulling same out of the hole and fixing the length of the contracting means remaining in the casing so as to shape the upper for a proper fitting on the wearer's foot.

VILEM FORSCHNER.
